WIRE-HOSE-CLAMP APPLYING DEVICE

George E. Conklin, Rushland, Pa.

Application December 4, 1947, Serial No. 789,643

5 Claims. (Cl. 81—9.3)

(Granted under the act of March 3, 1883, as amended April 30, 1928; 370 O. G. 757)

1

This invention relates to improvements in wire-clamping devices, and more particularly pertains to improvements in tools for drawing hose clamps securely around and in clamping engagement with hoses.

Wire-clamping devices in use presently are complex and cumbersome in use, being inoperative for many aircraft, marine and automotive applications because their structure and arrangement of elements make hoses to be secured inaccessible.

The primary object of this invention is to provide a simple and durable wire-clamping device adapted for use in aircraft, marine, automotive and like applications where the accessibility of the hose to be secured is a significant factor.

Another object is to provide a wire-clamping device that is compact, simple, and facile in use.

Still another object is to provide a wire-clamping device that can be manipulated with one hand.

A further object is to provide a wire-clamping device comprising a pistol-shaped clamp and a spring-loaded trigger feed thereon for the wire to be secured on a coupling.

Further objects and advantages of this invention, as well as its construction, arrangement and operation, will be apparent from the following description and claims in connection with the accompanying drawings, in which

Fig. 1 is an end elevation of a wire-clamping device showing a preferred embodiment of the invention;

Fig. 2. is a side elevation thereof, partly in section;

Fig. 3 is an end elevation of the nose portion thereof;

Fig. 4 is a plan view of said nose portion;

Fig. 5 is an isometric view of a hose coupling showing a clamping wire positioned thereon;

Fig. 6 is an isometric view of said hose coupling, showing another step in the operation of the wire-clamping device, and showing a portion of said device in phantom; and

Fig. 7 is an isometric view of said hose coupling showing a wire clamped thereon.

Similar numerals refer to similar parts throughout the several views.

The frame of the wire-clamping device comprises a hollow handle 11, which forms the stock or butt of the pistol shape defined, and a hollow barrel 13 integral with said handle and extending therefrom. Said barrel is preferably rectangular in cross-section, with the face distal said

2

handle open, and terminates in a tapered nose 15 having a plurality of locating holes 17 positioned on opposed faces of said nose and communicating with the interior of said barrel, and having a transverse groove 19 in the tip of said nose, for the purposes hereinafter described.

Fork 21 is carried slidably and non-rotatably in the portion of barrel 13 that is of uniform cross-section, said fork having a transversely serrated or notched interior base 23 and opposed upstanding tines or ears 25. Hollow screw 27, which is integral with fork 21, extends beyond the open end of said barrel distal said nose, said screw 27 being slidable freely in said barrel.

Cam 29 is provided with a transversely toothed portion 31, said cam being carried rotatably between ears 25 by means of pin 33. Said cam is carried at such eccentricity that rotation of said cam by means of integral lever arm 35 in a clockwise direction, as shown in Fig. 2, decreases the distance between the toothed portion 31 of said cam and the notched base 23 progressively, for the purposes hereinafter described.

Disc 37 is threaded on screw 27; retaining plate 39 is secured removably to handle 11, with screw 27 being slidable in a bore in said plate, so that disc 37 is carried at a notch in said handle in such manner that displacement of said disc relative to the barrel 13 is prevented. Said disc is provided with a plurality of ratchet teeth 41 disposed radially on a face of said disc, and the rim of said disc is knurled to facilitate manual rotation.

A trigger 43 is mounted rotatably on pin 45, which is carried in boxes in opposite faces of handle 11. A lug 47 integral with said trigger extends through an arcuate slot 49 in one face of handle 11, said slot being concentric the path of rotation of said trigger so that lug 47 is slideable therein. Pawl 51 is carried rotatably on lug 47 by means of washer 53, and compression spring 55 is secured between lug 47 and pawl 51 to maintain clockwise tension on said pawl, as shown in Fig. 2.

Compression spring 57 is secured between trigger 43 and the base 59 of handle 11 to maintain clockwise tension on said trigger, as shown in Fig. 2.

In operation, when it is desired to clamp a wire in such a manner as to couple a hose 61 to a conduit 63 on which said hose is positioned, a clamping wire 65 is doubled upon itself and then bent around the hose 61 (passing preferably twice around said hose). The free ends of said wire

65 are then passed through the loop formed by doubling said wire, as shown in Fig. 5.

The free ends of said wire 65 are then passed through a pair of holes 17 (accessibility determining whether the pair of holes 17 above or the pair below groove 19 is employed), then passed between the toothed portion 31 of cam 29 and the notched base 23 of fork 21, and then passed into the bore of screw 27, until suitable slack has been taken up to position groove 19 upon the crest of the loop of wire 65. Lever arm 35 is then rotated to clamp said wire securely between the toothed portion 31 and the notched base 23.

When trigger 43 is squeezed, pawl 51 engages one of the ratchet teeth 41 and thereby rotates disc 37 through an angle of several degrees, the distance of rotation being determined by the length of travel permitted lug 47 in slot 49. Upon release of the pressure exerted by the operator on trigger 43, said trigger is restored to its original position by compression spring 57, while pawl 51 is moved into engagement in the root of the next tooth of the ratchet wheel 41 by the travel of its axis, lug 47, in the slot 49 and by the rotative force of spring 65.

It is thus seen that upon each stroke of pawl 51 and resultant rotation of disc 37, screw 27 and its integral fork 21 and cam 29 are fed rectilinearly away from the nose of barrel 13, thereby drawing the free ends of wire 65 into barrel 13 while the groove 19 retains the looped end of said wire in selected position. It is thus apparent that repetition of this stroke a sufficient number of times is effective to tighten wire 65 on hose 61.

To cinch or clamp the wire 65, the wire-clamping device is rotated on the axis of groove 19 back over the looped portion or "standing" part of the wire, preferably for an angular distance of more than 90°. The disc 37 can then be backed off a number of turns to relieve tension, pawl 51 being disengaged from ratchet teeth 41 by rotation counterclockwise, as shown in Fig. 2. Then lever arm 35 is rotated to release the gripping engagement of the wire 65 effected by the cam and fork, and the wire-clamping device removed from the wire. Excess wire can then be cut off and the free ends of the wire 65 clinched upon the looped portion of said wire, as shown in Fig. 7, by means of a rawhide mallet.

It is apparent that, in lieu of the trigger-actuated feed hereinabove described, rapid take-up of the wire can be effected by manual rotation of disc 37, thereby permitting speedy operation in applications where accessibility of the hose to be clamped is not a significant factor.

Various modifications and changes can be made in the subject device without departing from the scope of the invention.

The invention described herein may be manufactured and used by or for the Government of the United States of America for governmental purposes without the payment of any royalties thereon or therefor.

I claim:

1. A wire-clamping device comprising a hollow frame element forming a handle, a hollow barrel fixed to and extending from said frame and terminating in a tapered nose portion having a plurality of openings communicating with the interior of said barrel, a clamp carried slidably in said barrel, and trigger-actuated means on said

handle to slide said clamp relative to said barrel.

2. A wire-clamping device comprising a hollow frame element forming a handle, a hollow barrel fixed to and extending from said frame and terminating in a tapered nose portion having a transversely grooved tip and a plurality of openings communicating with the interior of said barrel, an integral fork and screw carried slidably in said barrel, said fork having a transversely serrated inner base, a cam having a toothed portion mounted rotatably on said fork, whereby a wire can be gripped between said base and said toothed portion, and trigger-actuated means on said handle to slide said fork and screw rectilinearly relative said barrel.

3. A wire-clamping device comprising a hollow frame element forming a handle, a hollow barrel fixed to and extending from said frame and terminating in a tapered nose portion having a transversely grooved tip and a plurality of openings communicating with the interior of said barrel, an integral fork and screw carried slidably in said barrel, said fork having a transversely serrated inner base, a cam having a toothed portion mounted rotatably on said fork, whereby a wire can be gripped between said base and said toothed portion, a disc having radially disposed ratchet teeth on a face thereof threaded on said screw, means to prevent rectilinear movement of said disc, a trigger mounted rotatably on said handle, said trigger carrying a pawl that engages said ratchet teeth and rotates said disc, means to urge said trigger towards rotation in one direction, and means to urge said pawl towards rotation in said direction.

4. A wire-clamping device comprising a frame element forming a handle, a hollow barrel fixed to and extending from said frame element and terminating in a tapered nose portion having a plurality of openings communicating with the interior of said barrel, a clamp carried slidably in said barrel, and trigger-actuated means on said handle to slide said clamp relative said barrel.

5. A wire-clamping device comprising a frame element forming a handle, a hollow barrel fixed to and extending from said frame element and terminating in a nose portion having a plurality of openings communicating with the interior of said barrel, a clamp carried slidably in said barrel, and trigger-actuated means on said handle to slide said clamp relative to said barrel.

GEORGE E. CONKLIN.
